UNITED STATES PATENT OFFICE.

CHARLES L. BRYANT, OF CLEVELAND, OHIO.

HEATING APPARATUS.

Original application filed August 25, 1924, Serial No. 734,039. Divided and this application filed October 15, 1925. Serial No. 62,536.

My invention relates to heating and the principal object of my invention is to provide new and useful heating apparatus of the type and for the purposes herein disclosed. In the drawings accompanying this specification and forming a part thereof I have shown, for purposes of illustration, one form which my invention may assume. In these drawings:

10 Figure 1 is a front elevation of this illustrative embodiment of my invention,

Figure 2 is a side elevation of the device shown in Figure 1,

15 Figure 3 is a section on the line 3—3 of Figure 4,

Figure 4 is a section on the line 4—4 of Figure 3,

20 Figure 5 is a section on a line through the means securing the tank to its supporting ring, and the supporting ring to the boiler,

Figure 6 is a section on the line 6—6 of Figure 3, while

Figures 7 and 8 are reverse views of one end boiler section.

25 This application is a division of my application Serial Number 734,039 filed August 25, 1924.

The device herein shown comprises a boiler portion A, a tank portion B, and a fuel 30 supply and control portion C.

The boiler portion A comprises a plurality of like intermediate sections 11 flanked by a pair of like end sections 12. Each of these sections 11 and 12 is provided with two vertical passages 13 and 14 connected by a top cross passage 15, three intermediate cross passages 16, and a bottom cross passage 17, while the sections are placed in communication with each other by means of upper 35 and lower headers 18 and 19 formed by abutting annular projections 20 extending from each face of each section respectively at one upper corner of the section and at the lower corner of the section disposed diagonally 40 therefrom. Each joint between adjacent projections is rendered tight by means of a push nipple 21 received within annular recesses 22 in the engaged projections 20. The forward end of the header 18 is closed by 45 means of a thermostat 23 screw-threadedly engaging the interior of the end projection 20, the rear end of this header 18 communicates with an outlet conduit 24 screw-threadedly engaging that end projection 20, 50 the forward end of the lower header 19 is

closed by a plug 25 screw-threadedly engaging that end projection 20, while the rear end of this lower header 19 is in communication with an inlet duct 26 screw-threadedly engaging that end projection 20. 60

The end sections 12 are in turn flanked by a front end plate 27, provided with an aperture 28 for the thermostat 23 and a door 29 affording access to the interior and an opening 30 for the insertion of a fluid fuel burner 65 31, and a rear end plate 32, provided with an aperture 33 for the outlet duct 24 and an aperture 34 for the inlet duct 26 and an aperture (not shown) communicating with the interior of the vent duct 35. 70

Each of the sections 11 and 12 is provided on one side with an incomplete annular flange 36 and on the other side with a similar incomplete annular flange 37 arranged to seat inwardly of the flange 36 to provide a 75 staggered passage which may be readily closed by suitable material such as putty to thus seal the gap between adjacent sections over that portion of the periphery of the sections subtended by the flanges 36 and 37, 80 whereby such a seal is provided with sections all exactly alike over the body portion thereof. The front end plate 27 is provided with a flange 38 similar to one of the flanges 37 and therefore arranged to cooperate with 85 the flange 36 of the adjacent end section 12 while the rear end plate 32 is provided with a flange 39 similar to one of the flanges 36 and therefore arranged to cooperate with the flange 37 of the rear end element 12. 90 The space between sections remaining unsealed by the flanges 36, 37, 38, and 39 is normally closed by plates 40 each hung at its upper end from the two adjacent sections 11 or 12 or end plates 27 or 32 but removable 95 to expose the space between sections to permit cleaning thereof.

The sections 11 and 12 and the end plates 27 and 32 are secured together by means of tie rods 41 and 42 passing through apertures 43 and 44 in the sections 11 and 12, apertures 45 and 46 in the front plate 27, and apertures 47 and 48 in the rear plate 32, and screw-threaded to receive nuts 49 engaging the exterior faces of the end sections 12 to hold the sections 11 and 12 firmly together, and nuts 50 engaging the exterior faces of the end plates 27 and 32 to hold these plates firmly in position against the sections 11 and 12. 100

The sections 11 and 12 and the end plates 27 and 32 are supported by laterally projecting legs 51 formed integral with the end sections 12 and arranged to be secured to a base plate 52 by means of bolts 53 passing through apertures 54 in the legs 51 and corresponding apertures 55 in the base plate 52. These end sections 12 are also provided with upper laterally extending integral legs 56 arranged to carry a supporting ring 57 secured thereto by means of bolts 58 passing through apertures 59 in the legs 56 and cooperating apertures 60 in the supporting ring 57. The sections 11 and 12, and the end plates 27 and 32, are surrounded by an asbestos lined sheet metal casing comprising a cover 61 provided with a depending flange 62, a pair of side panels 63 and 64 held in position by the flanges 62 of the cover 61 and a flange 65 carried by the base plate 52, and a pair of end panels 66 and 67 held in position by these flanges 62 and 65 and also by the overhanging edges 68 of the side panels 63 and 64. The side panels 63 and 64 are cut away to permit the lateral projection of the legs 56 and 51, the front panel 66 is cut away to permit emergence of the thermostat 23 and door 29 and access to the burner aperture 30, and the rear panel 67 is apertured for the passage of the conduits 24 and 26 and the vent duct 35. The side panel 64 serves to maintain the plates 40 closely in position sealing the cleaning spaces between the sections 11 and 12 and end plates 27 and 32 yet at the same time is slightly shortened, whereby it may be slid upwardly within the flange 62 of the cover 61 a sufficient distance to bring the lower edge of the side panel 64 above the top of the flange 65 of the base plate 52 to thus permit ready removal of the panel 64 for access to and removal of the cleaning plates 40.

The cross passages 16 in the sections 11 and 12 are formed irregular in shape to 45 baffle the heating gases arising from the burner 31 and the end plates 27 and 32 are provided with baffles 69 arranged to cooperate with the exterior faces of the cross passages 16 of the end sections 12. The 50 location of the burner above the lower header 19 prevents the escape of heat downward and utilizes the heat thus ordinarily wasted to warm or preheat the fluid in the lower header 19 prior to its flow upwardly through 55 the passages 13, 14, 15, and 16 of the sections 11 and 12.

The tank portion B comprises a tank which may be of any suitable construction but is preferably of metal provided with a 60 suitable covering of heat insulated material. This tank 70 is provided with an intake conduit 71 connected to the supply main and extending to a point adjacent the bottom of the tank, an outlet conduit 72 extending to 65 the supplied system from the top of the

tank, a cold circulating fluid conduit 73 extending from the bottom of the tank to the intake 26, and a hot circulating fluid conduit 74 extending from the heater portion outlet 24 to a point adjacent the top of the tank. 70 The tank 70 is mounted within a flange 75 on the supporting ring 57 and secured in that position by means of bolts 79 passing through apertures 76 in the depending rim 77 of the tank 70 and thence through cooperating apertures 78 in the supporting ring 57. 75

The fuel feed and control portion C comprises a conduit 80 arranged to supply fuel to the burner 31, preferably intercepted by 80 a pressure reducer 81 designed to reduce the operating pressure below the minimum likely to exist in the supply main, and then intercepted by a valve 82 controlled by the thermostat 23. The thermostat 23 and valve 82 are not shown herein in detail because these elements do not in themselves form any part of my invention but may be of any suitable construction whereby increase in the temperature of the fluid surrounding the 90 thermostat tube 83 will reduce or shut off the supply of fuel to the burner 31 and decrease of temperature in the fluid adjacent the thermostat tube 83 will increase or recommence the supply of fuel to the burner 31. 95 In actual practice I have found satisfactory the thermostat manufactured by The Yoder-Thomas Manufacturing Company of Cleveland, Ohio. With this thermostat I utilize a pilot light supplied through a conduit 84 100 which intercepts the main conduit 80 ahead of the valve 82.

It will be apparent from the above description that I have provided a heater wherein the closing of the space between 105 sections is facilitated and accomplished, the cleaning strips readily and firmly positioned, the entire heat utilized, the tank secured and supported in a novel and improved manner, sufficient capacity provided to permit 110 the circulation of a large volume of fluid between the boiler and the tank, and the action of the heater controlled by the temperature of the fluid leaving the heater whereby the maximum temperature of the fluid may be predetermined and maintained below any critical temperature such as, in heating water, the temperature at which mineral matter is deposited or chemical action induced. Those skilled in the art will 115 readily find additional advantages in the device herein illustrated and will also readily realize that the particular embodiment of my invention herein shown and described may be variously changed and modified without departing from the spirit of my invention or sacrificing the advantages thereof. It will therefore be apparent that this disclosure is 120 illustrative only and that my invention is 125 not limited thereto. 130

I claim:

1. A boiler comprising a plurality of sections each provided on each face with an annular rib offset relative to the annular rib projecting from the adjacent face of the adjoining section, said ribs being incomplete annularly to provide apertures arranged to permit access to the space enclosed by said sections for the purpose of cleaning said 10 space, a plurality of plates one arranged to close each of said apertures, and a casing formed to surround said sections and arranged to closely engage said plates to hold said plates firmly in position sealing said 15 apertures.
2. A boiler provided with a plurality of sections formed to provide apertures formed by gaps in the flanges which elsewhere close the space between sections and arranged to 20 permit access to the space enclosed by said sections for the purpose of cleaning said space, a plurality of plates one arranged to close each of said apertures, and a casing formed to surround said sections and arranged to closely engage said plates to hold said plates firmly in position.
3. A boiler provided with a plurality of sections formed to provide apertures arranged to permit access to the space enclosed 30 by said sections for the purpose of cleaning said space, plate means arranged to close said apertures, and an asbestos lined casing formed to surround said sections and so arranged that said asbestos closely engages 35 said plate means to hold said plate means firmly in position.
4. A boiler provided with a plurality of sections formed to provide apertures arranged to permit access to the space enclosed 40 by said sections for the purpose of cleaning said space, a plurality of plates one arranged to close each of said apertures, and an asbestos lined casing formed to surround said sections and so arranged that said asbestos closely engages 45 said plates to hold said plates firmly in position.
5. A boiler comprising a plurality of sections each provided on each face with an annular rib offset relative to the annular rib 50 projecting from the adjacent face of the adjoining section, said ribs being incomplete annularly to provide apertures arranged to permit access to the space enclosed by said sections for the purpose of cleaning said 55 space, plate means arranged to close said apertures, and an asbestos lined casing formed to surround said sections and so arranged that said asbestos closely engages 60 said plate means to hold said plate means firmly in position sealing said apertures.
6. A boiler comprising a plurality of sections each provided on each face with an annular rib offset relative to the annular rib 65 projecting from the adjacent face of the adjoining section, said ribs being incomplete
- annularly to provide apertures arranged to permit access to the space enclosed by said sections for the purpose of cleaning said space, plate means arranged to close said apertures, and a casing formed to surround 70 said sections and arranged to closely engage said plate means to hold said plate means firmly in position sealing said apertures.
7. A boiler provided with a plurality of sections formed to provide apertures arranged to permit access to the space enclosed by said sections for the purpose of cleaning said space, plate means arranged to close 75 said apertures, and a casing formed to surround said sections and arranged to closely engage said plate means to hold said plate means firmly in position.
8. A boiler provided with a plurality of sections formed to provide apertures formed by gaps in the flanges which elsewhere close 80 the space between sections and arranged to permit access to the space enclosed by said sections for the purpose of cleaning said space, plate means arranged to close said apertures, and a casing formed to surround 85 said sections and arranged to closely engage said plate means to hold said plate means firmly in position.
9. A boiler provided with a plurality of sections formed to provide apertures arranged to permit access to the space enclosed by said sections for the purpose of cleaning said space, a plurality of plates one arranged to close each of said apertures, and a casing formed to surround 90 said sections and arranged to closely engage said plate means to hold said plate means firmly in position.
10. A boiler comprising a plurality of sections each provided on each face with an annular rib offset relative to the annular rib 95 projecting from the adjacent face of the adjoining section, said ribs being incomplete annularly to provide apertures arranged to permit access to the space enclosed by said sections for the purpose of cleaning said 100 space, a plurality of plates each arranged to close one of said apertures, and an asbestos lined casing formed to surround said sections and so arranged that said asbestos closely engages 105 said plates to hold said plates firmly in position.
11. A boiler comprising a plurality of sections, including a pair of end sections, each provided on its two faces with annular ribs offset one relative to the other, thereby to 110 be offset each relative to the annular rib on the adjacent face of an adjoining section, and end closures provided with annular ribs each offset relative to the annular rib on the adjacent face of the adjoining 115 end section.
12. A boiler comprising a plurality of sections, including a pair of identical end sections, each provided on its two faces with annular ribs offset one relative to the other, 120
- 130

thereby to be offset each relative to the annular rib on the adjacent face of an adjoining section, and end closures provided with annular ribs each offset relative to the annular 5 rib on the adjacent face of the adjoining end section.

13. A boiler comprising a plurality of sections, including at least one intermediate section, and a pair of identical end sections 10 identical with said intermediate section over the body part thereof, each provided on its two faces with annular ribs offset one relative to the other, thereby to be offset each relative to the annular rib on the adjacent 15 face of an adjoining section, and end closures provided with annular ribs each offset relative to the annular rib on the adjacent face of the adjoining end section.

14. A hot water generator unit including: 20 a boiler, for heating the water, comprising a plurality of sections; a water tank, for storing the water; ducts operatively connecting said tank with said boiler; and means independent of said ducts whereby said storage tank is supported by a plurality of said 25 boiler sections.

15. A hot water generator unit including: a boiler, for heating the water, comprising a plurality of sections, including supporting 30 sections which support said boiler; a water tank, for storing the water; ducts operatively connecting said tank with said boiler; and means independent of said ducts whereby said storage tank is supported by said sup- 35 porting sections.

16. A hot water generator unit including: a boiler, for heating the water, comprising a plurality of sections; a water tank, for storing the water; ducts operatively connecting said tank with said boiler; and means independent of said ducts whereby said storage tank is supported by a plurality of said 40 boiler sections identical with each other.

17. A hot water generator unit including: 45 a boiler, for heating the water, comprising a plurality of sections, including supporting sections which support said boiler and are identical with each other; a water tank, for storing the water; ducts operatively connecting said tank with said boiler; and means independent of said ducts whereby said storage tank is supported by said sup- 50 porting sections.

18. A hot water generator unit including: 55 a boiler, for heating the water, comprising a plurality of supporting sections; a ring secured to and supported by said sections; and a water storage tank secured to and supported by said ring.

19. A hot water generator unit including: 60 a boiler, for heating the water, comprising a plurality of supporting sections; a ring bolted to and supported by said sections; and a water storage tank bolted to and sup- 65 ported by said ring.

20. A hot water generator unit including: a boiler, for heating the water, comprising a plurality of sections each provided with feet projecting upwardly therefrom; and a water storage tank secured to and supported by said feet. 70

21. A hot water generator unit including: a boiler, for heating the water, comprising a plurality of sections each provided with feet projecting upwardly therefrom; a ring 75 secured to and supported by said feet; and a water storage tank secured to and supported by said ring.

22. A hot water generator unit including: a boiler, for heating the water, comprising a 80 plurality of sections each provided with feet projecting upwardly therefrom; a ring bolted to and supported by said feet; and a water storage tank bolted to and supported by said ring. 85

23. A boiler or water heater comprising: a series of sections arranged side by side, each section having front and rear conduit portions and spaced transverse ducts communicating at their ends with the conduit 90 portions, the ducts having on opposite sides of a vertical section longitudinally disposed lateral extensions, those on one side being formed on the upper portions of the ducts and those on the other side being formed on the lower portions of the ducts, the ducts of the adjacent sections being spaced to provide 95 passageways for heated gases.

24. A boiler or water heater comprising: a series of sections arranged side by side, 100 each section having front and rear conduit portions and superposed spaced transverse ducts extending between them, the ducts of adjacent sections having overlapping extensions, the extensions running longitudinally 105 of the ducts on both sides of each section, those on one side being formed on the lower portions of the ducts and those on the other side being formed on the upper portions of the ducts, the ducts of the adjacent sections being spaced to provide 110 passageways for heated gases. 110

25. A boiler or water heater comprising: a series of sections arranged side by side, each section having front and rear conduit 115 portions and a plurality of superposed spaced ducts which communicate at their ends with the conduit portions and are formed on opposite sides with lateral extensions which are disposed longitudinally 120 of the ducts and overlap the extensions of the ducts of the adjacent section or sections, the duct extensions on one side of a section being formed on the lower portions of the ducts and those on the other side being formed on the upper portions of the ducts, the ducts of the adjacent sections being 125 spaced to provide passageways for heated gases.

26. A boiler or water heater comprising: 130

- a series of similar sections arranged side by side and composed of front and rear upright conduit portions joined by spaced transverse substantially Z-shaped ducts, the said ducts of the adjacent sections being spaced to provide passageways for heated gases, and the ducts of one section overlapping ducts of the adjoining section or sections.
27. A boiler or water heater comprising: a series of similar sections arranged side by side and composed of front and rear upright conduit portions joined by spaced transverse substantially Z-shaped ducts, the said ducts of the adjacent sections being spaced to provide passageways for heated gases, the ducts of one section being horizontally aligned with ducts of the adjoining section or sections and having projecting portions which overlap to form tortuous passage- ways between the sections.

In testimony whereof I hereunto affix my signature.

CHARLES L. BRYANT.
